UNITED STATES PATENT OFFICE.

DAVYDD C. HUGHES, OF CHICAGO, ILLINOIS, ASSIGNOR, BY MESNE ASSIGNMENTS, TO
ADDRESSOGRAPH COMPANY, OF CHICAGO, ILLINOIS, A CORPORATION OF ILLINOIS.

PRINTING AND ADDRESSING MACHINE.

1.151,950.

Specification of Letters Patent. Patented Aug. 31, 1915.

Application filed July 5, 1911. Serial No. 636,934.

To all whom it may concern:

Be it known that I, DAVYDD C. HUGHES, a citizen of the United States, residing at Chicago, in the county of Cook and State of Illinois, have invented new and useful Improvements in Printing and Addressing Machines, of which the following is a full, clear, concise, and exact description, reference being had to the accompanying drawing, forming a part of this specification.

My invention relates to improvements in printing and addressing machines and is particularly designed for printing and addressing circular letters, statements and the like.

One of the objects of my invention is to provide a machine wherein circular letters or the like, each having a different address, may be printed, which machine will be rapid in operation and will give to the letters all the appearances of having been written on a typewriter.

Another object of my invention is to provide means whereby the character of the salutation of the letter may be caused to correspond with the address; that is, if the letter is addressed to a woman the salutation will correspond therewith, if the letter is addressed to a corporation the salutation will be automatically changed to correspond to the address, and if the letter is addressed to a man the salutation will likewise be automatically changed to correspond to the address. Also, if desired, the salutation may be left blank.

Another object of my invention is to provide means whereby letters for certain predetermined addresses of a list will not be printed, at the same time permitting the address carrying members to pass through the machine so that their arrangement in the list will not be disturbed. For instance, in some businesses the mailing list is arranged according to States and the lists of each State contain addresses to customers in different lines of business; for example, wholesale grocers and retail grocers. In sending out a letter it may be desirable to send it to the wholesale grocers only and at the same time it would not be desirable, advantageous nor consistent with speed to go through the entire list and pick out only the address plates for the wholesale grocers. To this end, therefore, my machine is so constructed that it may be caused to be thrown out of print.

ing operation when any predetermined address carrying member passes through the machine.

Various other objects of my invention and advantages derived therefrom will appear in the accompanying specification.

For the purpose of disclosing my invention, I have illustrated one embodiment thereof in the accompanying drawings.

In said drawings,—Figure 1 is a side elevation of a machine embodying my invention; Fig. 2 is a top plan view thereof; Figs. 3 and 4 when taken together constitute a complete sectional view taken on the line 3—3 of Fig. 1; these two figures, 3 and 4, meet on the dotted line y—y; Fig. 5 is a side elevation of my machine looking in a direction opposite to that of Fig. 1, having certain portions thereof in section and having the inclosing casing of certain operating parts removed; Fig. 6 is a sectional view taken on the line 6—6 of Fig. 3; Fig. 7 is a sectional view taken on the line 7—7 of Fig. 4 looking in the direction of the arrows; Fig. 8 is a sectional view taken on the line 8—8 of Fig. 5; Fig. 9 is a detail section of the motor driving mechanism for my machine and is taken on the line 9—9 of Fig. 10; Fig. 10 is a sectional detail view of the same mechanism taken on the line 10—10 of Fig. 9; Fig. 11 is a sectional detail view of the same mechanism taken on the line 11—11 of Fig. 9; Figs. 12, 13 and 14 are detail views of parts of the driving mechanism; Fig. 15 is a detail plan view of parts thereof being in section, of the operating mechanism for the paper delivering device; Fig. 16 is a plan view of the plate packing mechanism; Fig. 17 is a detail plan of the mechanism for throwing the machine out of printing operation when a plate passes through for which it is not desired to print a letter; Fig. 18 is a detail section on the line 18—18 of Fig. 17; Fig. 19 is a detail elevation of one of the tripping arms; Fig. 20 is a detail of the depressor clips to be attached to the addressing plate; Fig. 21 is a sectional view of the printing plate showing the depressor clip in position; Fig. 22 is a detail sectional view of the throwout mechanism for throwing the machine out of printing operation, taken on the line 22—22 of Fig. 3; Fig. 23 is a detail view of this same mechanism taken on the line 23—23 of Fig. 3; Fig. 24 is a detail view of

the gear drive for the platen; Fig. 25 is a detail plan of the tripping mechanism for changing the salutation; Fig. 26 is a sectional view of the salutation changing mechanism, taken on the line 26—26 of Fig. 25; Figs. 27, 28 and 29 are detail elevations of the salutation tripping stop members; Fig. 30 is a detail elevation of the salutation changing mechanism, taken on the line 10 30—30 of Fig. 25; Figs. 31, 32, 33, 34, 35 and 36 are diagrammatic views illustrating the operation of the salutation changing mechanism; Fig. 37 is a diagrammatic view showing the salutation device in non-printing or blank position; Fig. 38 is a detailed view of the salutation locking means; Fig. 39 is a sectional detail view of the salutation changing mechanism taken on the line 15 39—39 of Fig. 26, the parts, however, being 20 shown in a slightly different position than in Fig. 26; Fig. 40 is a plan view of a type plate, showing the depressor lugs on the type plate for causing the salutation to be changed; Fig. 41 is a sectional view taken 25 on the line 41—41 of Fig. 40; and Fig. 42 is a detailed section on the line 42—42 of Fig. 7.

In order that the construction and operation of the machine may be more fully understood, I will first describe, in general, the 30 operation of the machine. The embodiment of the machine illustrated contemplates the printing of a circular letter which is the same on each sheet printed. Each circular 35 letter, however, will have a separate address and may have a different salutation the character of which would depend on the address. These letters are all dated and the impression for all of the printed matter on 40 the sheet is made through an inking ribbon. To accomplish the above result in the machine illustrated with the greatest possible speed, I contemplate the use of a rotating printing or type bed on which the body of 45 the letter is adapted to be set up in metal type, the characters of which resemble the characters of a typewriter. In addition to the type bed I provide a rotating type plate bed which is mounted upon the same shaft 50 as is the printing bed and over which pass type plates having the different addresses set up thereon in type similar to those used on the type bed. On the type bed I preferably mount a salutation device having set up 55 thereon in similar type a number of different salutations which are adapted to be automatically changed to correspond to the addresses on the type plates. I also use a rotary platen which is arranged above the 60 printing and type plate beds and bears upon the sheet to be impressed with sufficient pressure to cause the type on a type plate passing over the type plate bed and on the type bed to make the proper impression through a 65 suitable inking ribbon. I also provide means

for feeding the paper and type plates at predetermined intervals to the printing mechanism.

In addition to the above described devices, I provide means for automatically changing 70 the salutation to cause it to correspond to the address of the letter. This mechanism is set in operation by the type plates as they pass to the type plate drum. Also, I provide a mechanism for automatically throwing the 75 machine out of printing operation when a plate passes therethrough carrying an address to which no letter is intended to be sent. This tripping mechanism is particularly adaptable for use where it is desired 80 only to send letters to a certain portion of the mailing list. This tripping mechanism, likewise, is thrown into operation by the address plates as they pass through the machine. 85

Describing now specifically various parts of the machine: The entire mechanism is mounted in or on a suitable frame which maintains the various parts in their proper operative relation with respect to one another. This frame consists generally of two side members 2 rigidly held together at the bottom by bolts or cross rods 3 and suitable spacer beams 4. The frame is preferably made skeleton in form to reduce as much as 90 is consistent with rigidity and strength the weight thereof. It has various extensions for accommodating the different mechanisms and wherever possible these extensions are formed as housings or casings to protect the 95 parts of the machine from damage and dirt, and to prevent the various gears, etc., from presenting mechanism which is liable to catch the operator's hands or clothing. The top of the upper portion of the frame is provided with a bed 5 which extends substantially the length of the frame and serves as a support and guide for the type plates 6 which are contained in a magazine 7 mounted at the rear of the machine and extending 100 vertically therefrom. The magazine is open at the front and is adapted to contain a stack of type plates, the plates being held against withdrawal by a pair of inwardly projecting flanges 8 mounted on hinged plates 9 and 105 adapted to engage ears 10 on the type plates. The bottom portions of the flanges 8 are cut away so that one plate at a time may be withdrawn from the bottom of the stack. 110

The printing mechanism.—In the embodiment of my machine illustrated, the printing mechanism, as clearly shown in Fig. 8, consists principally of a rotary type bed 11, a rotary type plate bed 12, and a platen 13. The type and type plate beds are co-axial 120 and are mounted upon a shaft 14 which is journaled in suitable bearings in the frame and may be rotated by a crank handle 15 connected thereto or by a suitable power driving mechanism. The bed 11 is intended 125

for printing the main or body portion of the letter. The type plate bed 12 acts as a rotary bed over which the type plates are adapted to pass during their printing operation. The platen 13 is smaller in diameter than the two beds heretofore described and is provided with a rubber or composition platen surface 16 so as not to injure the printing type. This platen 13 is mounted 5 in a swinging or auxiliary carriage 17 which is pivoted at 18 to the sides of the frame whereby the carriage may be swung upwardly and the platen widely separated from the beds so access may be gained to 10 the mechanism below the carriage and for other purposes.

The platen 13 may be readily removed from the carriage without disturbing its adjustment, one end thereof being centered 15 and held in position by a removable pin 19 locked in the frame by a thumb screw 20, while the other end has a separable connection with the driving shaft 21 journaled in the carriage. The shafts 14 and 21 are connected by a suitable gear mechanism to be 20 described more fully hereinafter, and the gears of this mechanism are so proportioned that the peripheral speed of the platen is the same as the peripheral speed of the type 25 bed when the type are in position thereon; that is, with the speed of the greatest periphery of the type bed.

I provide two rotary beds so that the body 30 of the letter, which remains the same for each of any number of sheets printed, may be printed on each sheet as it passes through the machine, and at the same time a separate address may be impressed on each sheet as it passes through the machine. By the provision 35 of two beds, the subject matter which is to remain the same throughout may be set up on one, while the subject matter which is to be changed may be set up on a plurality of separate plates adapted to pass over the second bed. The body portion of the article 40 to be printed is set up upon a separable type holder or chase which is removable from the machine to permit the composing of the subject matter and is afterward placed in position 45 on the type bed. This chase or type bed consists of a curved plate 22 (see Figs. 3 and 4) conformed to the shape of the bed 11 and may be of such length as to embrace as much of the bed as necessary. 50 In practice I prefer to make it only of sufficient length to embrace substantially half the circumference of the bed. This plate has formed thereon a plurality of T-shaped ribs 23 which extend peripherally 55 of the bed to form a plurality of type channels adapted to receive metal type, the characters of which have the same characteristics as the characters of the type on a type-writing machine. The inner end of the 60 curved plate is adapted to fit an undercut shoulder 24 on the inner end of the type bed to prevent the chase from becoming displaced and the other end of the plate is adapted to be secured on the bed by means of screws 25 arranged to fit into screw holes 70 in the periphery of the bed. These screw holes are arranged at various intervals around the bed whereby the position of the plate thereon may be changed if desired. The type may be locked in the channels of 75 the chase in any suitable manner and I have not disclosed in the accompanying drawings any specific means for doing so. Such a means may consist, if desired, of a strip secured to one end of the plate and closing the 80 ends of the channels, whereby the type will be prevented from dropping out of the channels at this end. The opposite end of the lines of type in the channels may be locked in by locking blocks arranged to be secured in 85 the channels.

The type plate bed 12 is mounted to rotate independently of the type bed and, in view of the fact that the type plate must ride over the same and at the same time the 90 type of the type plate must be in the same printing plane as the type on the letter bed, this type plate bed is smaller in diameter than the type bed when the type are set up thereon. To state it differently, the diameter of the type plate bed is smaller than the diameter of a circle passing around the periphery of the type on the type bed. However, when a type plate passes over the type 95 plate bed, the speed at which it moves must be exactly the same as the peripheral speed of the type on the type bed; therefore, even though the diameter of the type plate bed is less than that of the type bed, the two beds must be driven at the same peripheral 100 speed. To this end, therefore, the type plate bed is mounted to rotate independently of the type bed, and in the embodiment illustrated is freely mounted on the shaft 14 and is driven by the platen 13, Fig. 8, which, as 105 we have heretofore seen, operates at the same peripheral speed as the peripheral speed of the type bed. The driving of the type plate bed by the platen 13 is accomplished through the friction of the platen 110 and the type plate and of the type plate on the type plate drum, as the type plate passes beneath the platen. To this end the type plate bed is mounted to freely rotate on the shaft and in order that the friction may be 115 reduced as much as possible, the type plate bed is provided with ball bearings 26. The space above the peripheral surface of the type plate bed and beneath the surface of the platen 13 is just sufficient so that when 120 a type plate is in this space the face of its type will be in the printing plane of the type 125 on the type bed.

The bed 11, when a circular letter is being 130 printed, rotates with the shaft 14, and to

this end it is locked to the shaft through the medium of a locking pin 27 (see Fig. 4) adapted to engage in an opening 28 in a sprocket 29 keyed to the shaft 14. The purpose of this sprocket is to operate one of the ribbon rolls, and the same will be more. 5 fully described hereinafter; sufficient at this time to say that this sprocket is keyed to the shaft and is provided with the opening 10 28 whereby through the medium of the pin 27 the type bed is locked to the shaft. The pin 27 is mounted in a suitable casing 30 mounted on the head 31 of the drum forming the type bed, and interposed between 15 the shoulder 32 on the pin and the rear end of the casing 30 is a coiled spring 33 which is adapted to hold the pin normally in its forward or locking position. In order that the type bed may be disconnected from the 20 shaft 14 to permit the shaft to be rotated without rotating the letter drum, I provide a disconnecting mechanism which consists of a wedge 34 mounted within a guide 35 and connected at 36 to an operating lever 25 37 pivoted to the frame at 38 and provided with a handle 39 extending to the exterior of the frame of the machine through a slot 40 in said frame. The wedge 34 when the handle 39 is turned forward is moved into 30 the path of the pin 27 and as the pin rotates with the head 31 a shoulder 41 on the pin engages the wedge and the pin is forced transversely and out of the opening in the sprocket. A suitable stop 42 is provided on 35 the wedge against which the end of the locking pin 27 engages, to prevent a continued rotation of the type bed due to friction between the parts. This disconnecting mechanism is particularly useful in event it 40 is desired to use the machine for printing an address alone, say for instance, when it is desired to use the machine for printing an address on a number of envelopes. In this event, the handle 39 would be thrown 45 to disconnect the type bed from the driving shaft and the machine run merely to operate the addressing portion without rotating or operating the letter printing portion.

The driving mechanism.—As before 50 stated, the shaft 14 is mounted in suitable bearings in the frame and these bearings, as illustrated at 43, are ball bearings, in order to reduce as much as possible the friction between the parts of the machine and in 55 order that the machine may run as easily as possible. This is particularly desirable in view of the fact that the machine may be operated by hand. The machine is illustrated as being provided with either hand or 60 power driving mechanism and to this end it is necessary that some means be provided whereby the crank handle for operating the machine be permitted to remain stationary when the machine is being driven by power; 65 likewise it is desirable that the power mech-

anism be disconnected when the machine is operated by hand, in order to reduce as much as possible the load necessary to be driven by manual means. To this end, therefore, I provide a driving mechanism, 70 Figs. 9 to 14, which may be operated either by means of the crank 15 or by a driving pulley 44 belted to a suitable power machine, such for instance as an electric motor. The crank is mounted on a stub shaft 45 journaled in the frame of the machine and this stub shaft has mounted thereon a pinion 46 which is adapted to mesh, through an idler 48, with a gear 47 connected with the driving shaft 14 through the medium of 75 a uni-directional clutch mechanism. This uni-directional clutch mechanism is so arranged that as long as the crank handle 15 is rotated in a clockwise direction the gear 80 47 will be connected to the shaft 14 and the shaft will be rotated. If, however, the crank is rotated in a counter-clockwise direction, the gear 47 will immediately be disconnected from the shaft 14 and the shaft will not be 85 driven.

The driving pulley 44 is mounted on a stub shaft 49 mounted in suitable journals in the framework and this stub shaft is provided with a pinion 50 adapted to mesh with a gear wheel 51. The gear wheel 51 is mounted upon a stub shaft 52 provided with a pinion 53 adapted to mesh with a gear wheel 54 corresponding to the gear wheel 47, and connected with the shaft 14 through the medium of a uni-directional 90 clutch mechanism. This uni-directional clutch mechanism, like the clutch mechanism for the crank 15, will connect the gear wheel 54 with the shaft only when the gear wheel is rotated in a clockwise direction. 95 It will be noted, however, that due to the gear connection between the pulley 44 and the gear wheel 54, with the pulley rotating in a clockwise direction the gear wheel will be rotated in the same direction. The construction of the two uni-directional clutch mechanisms is the same and is more fully 100 illustrated in Fig. 13. Referring to this figure, it will be noted that the shaft 14 is provided with a sleeve 55 which is adapted to rotate therewith. This sleeve has keyed thereon a hub 56, which hub is provided with a pair of right angled notches 57 in its periphery. The gear wheels 54 and 47 are mounted on the hub 56, being held in position by suitable collars 58 and 59 and spaced apart by a collar 60. These collars also serve to retain in the notches small rollers 61 which have some play in the notches, but which are constantly pressed by spiral springs 62 into the gradually narrowing spaces formed between the inner curved faces of the gear wheels and the flat bottoms of the notches. Due to this construction, 110 when say the gear wheel 47 is rotated in a 115

120 125 130

clockwise direction, the rollers 61, due to the influence of the coiled springs 62 and the frictional engagement of the rollers with the sides of the slot formed by the inner curved 5 surface of the gear wheel and the flat bottom of the notches, will tend to roll down into the narrower portion of the space in which they are arranged, thereby locking the gear wheel 47 to the hub 56 and rotating the shaft with the gear 47. If, however, the gear 47 remains stationary, which would be the case if the shaft 14 were driven from pulley 44, then the hub 56 rotating in a clockwise direction would disengage the 10 rollers 61 from the curved surface of the gear wheel and force the same toward the larger portion of the space in which the rollers are arranged. This is due to the fact that when the hub 56 rotates in a clockwise 15 direction the flat bottoms of the notches will tend to engage the rollers 61, thereby forcing them toward the rear of the notches against the tension of the springs 62. By this clutching mechanism, it will be seen that when the machine is driven by power 20 the crank and its gearing is disconnected and when the machine is operated manually the pulley 44 and its gearing is disconnected. As before stated, the sleeve 55 is adapted 25 to rotate with the shaft 14. It is locked to the shaft by a pair of friction disks 63 and 64. The disk 63 is keyed on the sleeve 55 and is provided with an annular slot 65 T-shaped in cross section to receive the 30 headed pins 66 which project through holes in the disk 64 and are provided with thumb nuts 67 to draw the two disks together. The disk 64 is keyed on the shaft 14, and it will therefore be seen that any movement 35 imparted to the disk 63 through the sleeve 55 will be transmitted to the shaft 14. By loosening the thumb nuts 67 the disks may be moved relatively, the disk 63 being graduated for determining the extent of the 40 movement. The purpose of this relative movement will appear more fully hereinafter.

The conveyer mechanism.—The type plates contained in the magazine 7 at the rear of the machine are removed therefrom one at a time and fed forward to the type plate bed by means of a suitable conveyer mechanism. This conveyer mechanism comprises a chain 68 which is provided with 45 suitable type plate engaging dogs 69 projecting therefrom and arranged at regular intervals on the chain. The chain travels over the bed 5 in a suitable recess 70 formed therein and is carried over a pair of sprocket 50 wheels. One of the sprocket wheels is arranged on a shaft 71 mounted in the rear end of the frame and inclosed in a suitable casing 72. The other sprocket wheel 73 is co-axial with the type plate bed and is suitably mounted upon a drum 74 keyed to the

shaft 14. One portion 75 of this drum provides a rotating bed over which a portion of the type plate is adapted to pass. As there is no pressure exerted upon the type plate at the point where it passes over the portion 75, it is not essential that this drum be rotated at the same peripheral speed as the type bed 11. There being no pressure upon the type plate at this point, the type plate may slide slightly on the drum. This 75 drum is also provided with a recessed portion 76 in which is arranged to be secured a suitable dater or dating mechanism 77.

The salutation mechanism.—The salutation, such as "Dear Sir," "Dear Madam," "Gentlemen," etc., which is adapted to be printed upon the letter must be changeable so that the form thereof will agree with the address. In this type of machine in which all of the work is performed automatically, 80 it is desirable that the salutation be changed automatically so that the salutation of the letter shall agree with the address of the letter; that is, so that when the letter is addressed to a woman the salutation will be 85 "Dear Madam" or "Dear Miss" as the case may be. When the letter is addressed to a firm the salutation will be "Gentlemen," and if the letter be addressed to a man the salutation will be "Dear Sir." To this end I 90 have provided means set in motion by the passage of the type plate over the bed of the machine and to the printing mechanism for changing the salutation. The salutation device and its operating mechanism, together 95 with the means for setting in motion the changing mechanism, are illustrated in detail in Figs. 25 to 41.

Referring first to Figs. 26 and 39, as these figures show more clearly the method of 100 mounting the salutation mechanism in the machine, the salutation supporting member consists of a four-sided block 78 which is mounted on the end of a stub shaft 79 supported in a journal 80 extending inwardly 105 from the head 81 of the drum forming the type bed 11. The four sides, 82, 83, 84 and 85, are arranged when in printing position, to be flush with the periphery of the empty type bed, so that the type on the salutation 110 block will be in the same printing plane as the type on the bed 11. These four sides are slightly curved to conform to the periphery of the bed 11 and each side is provided with a T-shaped channel 86 in which the various 115 type for printing the salutation are arranged to be secured. The inner end of the stub shaft 79 has mounted thereon a rotatable hub 87 having formed thereon a pair of pinions 88 and 89. The pinion 88 is adapted 120 to mesh with a curved rack 90 rotatably mounted on a hub 91 extending inwardly from and integrally formed with the head 81. The pinion 89 is adapted to mesh, through an idler 92, with a segmental curved 125

rack 93, likewise rotatably mounted on the hub 91. This mechanism forms the mechanism for rotating the salutation block 78 in order to move the different salutations to 5 printing position.

In order that the salutation block 78 may be properly centered, when it is once moved to its proper position, the block is provided with four V-shaped recesses 94 on 10 its inner face, in which is adapted to project a centering pin 95 mounted in the head 81 and forced inwardly or into engaging position by a coiled spring 96 interposed between the head of the pin and the rear of 15 the casing. The V-shaped recesses 94 are so positioned that when the pin 95 enters the same, the type carrying edges of the block will be centered in proper printing position with the type in proper alinement with the 20 type on the bed 11. The curved segmental rack 90 has secured thereto a substantially radially extending arm 97. The rack 93 is likewise provided with a similar arm 98. These arms are not quite long enough to 25 extend to the periphery of the bed 11, but are of sufficient length to be engaged by stops arranged to be projected into their path. In order that the arms may be engaged by the stops, the bed 11 is provided with a slot 99 30 which is of sufficient width to accommodate the stops and which extends about half way around the periphery of the bed. At the point where the gears 88 and 89 are mounted, the slot is slightly increased in width to 35 accommodate these gears which, however, do not project beyond the periphery of the bed.

For engaging and holding the arms 97 and 98 against movement, I provide three 40 reciprocal stops 100, 101 and 102. These stops are mounted in slots formed in a suitable block 103 secured beneath the bed 5 of the machine, and are provided with longitudinally extending slots 104 through which 45 are adapted to extend supporting pins 105 mounted in the block 103. The two stops 100 and 102 are each of only sufficient width in cross-section to engage, when projected into their path, the respective arms 97 and 98, while the center stop 101 is of sufficient 50 width to engage, when projected into their path, either of the arms 97 and 98. The stops 100, 101 and 102 are respectively pressed forward or into an engaging position 55 by spring-pressed pins 106, 107 and 108 and are held against forward movement under the influence of the spring-pressed pins by the respective triggers 109, 110 and 111, each of which is adapted to engage a shoulder 112 formed on each of the stops. The 60 portion of each of the stops immediately in front of the shoulder 112, is cam-shaped as at 113 for purposes which will hereafter be more fully understood in describing the 65 operation of the machine.

The shoulders 112 on the stops are so related that the trigger of one stop member will not affect the operation of the trigger of the other stops. The three triggers 109, 110 and 111 extend at right angles to the 70 stops and are pivotally mounted in a supporting block 114 mounted beneath the bed 5 of the machine. The shortest trigger 111 is tripped by a tripping lever 115; the next longest is tripped by a tripping lever 116; 75 and the next or longest trigger 109 is tripped by a tripping lever 117. These three levers extend at right angles to the triggers, or longitudinally of the bed of the machine, and are pivoted in a block 118 extending 80 from the under side of the bed 5. When the rear end of one of these levers is depressed, the front end will be raised and will thereby raise the rear end of one of the triggers and depress the front end, disengaging the triggers from the shoulders 112 of the stops. 85 The rear ends of the tripping levers 115, 116 and 117 are adapted to be depressed by suitable lugs or depressors formed on the type plate. These depressors on the type plate 90 illustrated take the form of integrally formed lugs 119, 120 and 121. Before the address is set up on the type plate these lugs are parallel with the bottom of the plate. When, however, the address is set up, 95 the proper salutation lug or depressor is bent down. For instance, if the address on the type plate is "Dear Madam," then the proper depressor for tripping the lever which controls the movement of the salutation to "Dear Madam" would be bent down so that when the type plate passes through the machine this depressor would engage the proper tripping lever. I have illustrated in Fig. 25 the center depressor 120 as 100 being bent down and this depressor would be adapted to engage and depress the rear end of the tripping lever 116. As the depression of the levers 115, 116 and 117 depends merely upon the weight of the type 105 plate, and as this weight is not great, I have found it advisable to make the tripping levers very sensitive in their operation. To this end, therefore, I have provided means other than the triggers 109, 110 and 111 for 110 normally holding the stops out of engaging position. This forward pressure of the pins 106, 107 and 108 is considerable, and if no means were provided for relieving the triggers, the friction between the shoulders 112 120 on the stops and their triggers would be sufficiently great to interfere with the depressing of the tripping levers. The forward portion of each of the stops is provided with a shoulder 122 in the path of a 125 reciprocating pusher pin 123 mounted upon an arm 124 carried on a shaft 125 which is suitably supported in journals formed in the frame of the machine. A cam arm 126 is mounted on the shaft 125 and is provided 130

with a roller 127 adapted to be engaged by the cam surfaces 128, 129 and 130 formed on a cam wheel 131 secured on the drum 74. This cam wheel 131, therefore, is adapted to 5 rotate with the shaft 14 and the cam surfaces are so proportioned that normally the stops are held back by the pusher pin 123 and are only held by the triggers for a short period when the pusher pin moves to permit 10 the stops to move forward. This, however, does not occur until after the plates on their passage through the machine have moved past the point where they depress the tripping levers.

15 In order to properly understand the operation in changing a salutation so that it will correspond to the address, reference will be had particularly to Figs. 31 to 37. These figures show a portion of the mechanism 20 diagrammatically and illustrate more clearly the operation thereof.

The salutation block, as before mentioned, is provided with four type-carrying faces. For the purpose of illustration, we will assume that the face 82 has the salutation "Dear Sir" thereon. This is the salutation most generally used. The face 84 has the salutation "Gentlemen" set up thereon, this being the salutation which perhaps is the 30 next most generally used; and the face 85 has the salutation "Dear Madam" thereon. The other face 83 is left blank.

We will assume that the last salutation printed by the machine was "Dear Sir," 35 which, it will be remembered, is set up on the face 82 of the salutation block. We will now assume that the next type plate which is to pass through the printing mechanism has an address to a firm set up thereon.

40 When the address was set up on the type plate the depressor 121 was turned down so that as the address plate passes over the bed the turned down depressor 121 will engage the top of the rear end of the lever 117, de- 45 pressing the rear end of the lever. During the period that the type plate passes over the tops of the tripping levers and until after the address plate has completely passed the engaging portions of the tripping

50 levers the roller 127 will be riding on the cam surface 128 of the cam 131. The pusher pin 123 will therefore be holding the stops against forward movement and these stops will be held rearwardly so far that the cam 55 surfaces 113 will be holding the triggers depressed, and the only weight which must be moved by the depressor 121 is the front end of the lever 117. As soon, however, as the roller 127 moves off the cam surface 128 the

60 pusher pin will permit all of the stops to move forward under the influence of their respective spring-pressed pins. However, as the forward ends of the two tripping levers 115 and 116 are not raised, the triggers 110 and 65 111 will ride upon the cam surfaces 113 of

their respective stops 101 and 102 and engage the shoulders 112, holding the stops against forward movement; but it will be remembered that the front end of the lever 117 is raised, so that the front end of the trigger 109 is maintained depressed and out of the path of the shoulder 112 on the stop 100, permitting the stop to move forward into the path of the arm 97. The parts will now be in the position shown in Fig. 31 75 with the salutation block 78 revolving about the center of the rack 90 and with the rack held stationary by the engagement of the stop 100 with the arm 97. As the block continues to revolve with the type bed, the pinion 88 engaging the rack 90 will rotate the salutation block 78. This rotation of the salutation block will continue until the roller 127 rides up the cam surface 129, which will cause the pusher pin 123 to retract or move 80 out of holding position the stop 100 and the arm 97 to thereby be released, the salutation block, however, having been rotated to present the face 84 to printing position, or to the position shown in Fig. 32. By the time 90 the salutation block has rotated with the bed 11 to the position shown in Fig. 32, the arm 98 will have reached the position shown therein and ahead of the arm 97, as this arm 98 has not been held against movement. 95 When the salutation block has reached the position illustrated in Fig. 32, it will have reached a position to be locked against further rotation on its own axis by means of the stationary cam 132. This cam surrounds the shaft 14 and is rigidly mounted and held in position by a supporting arm 133 which depends from the bottom of the bed plate of the frame. As particularly shown in Fig. 38, one side of the salutation 100 block is provided with a plurality of convex shoulders 134, which shoulders conform to the shape of the cam 132. This cam is so located relative to the salutation block that as the salutation block is revolved with the bed 11 to its printing position the cam 132 will engage one of the shoulders 134 and this engagement will continue until the printing operation is performed by the salutation block, after which the shoulder 134 110 will move off the cam 132 and the salutation block will again be free to rotate to present a different salutation. It will thus be seen that the salutation block, during the period 115 in which it passes through its printing operation, is securely locked against rotation. 120

We will now assume that the next plate which is adapted to pass through the printing mechanism carries on it an address to a woman. It is therefore desirable that the 125 salutation be "Dear Madam." When the address was set up on the type plate the depressor 120 was turned down. Therefore, as the type plate moves over the tripping levers the rear end of the tripping lever 116 130

will be depressed. This operates the trigger 110, which permits the center stop 101 to be projected in the path of the arms 97 and 98. It will be noted in Fig. 32 that the arm 98 is leading in the movement of the arms around the shaft 14. As the stop 101 is of sufficient width to engage either one of the arms 97 and 98, and as the arm 98 is the leading arm, this will be the first arm to be engaged by the stop 101. The stop 101 when it engages the arm, as illustrated in Fig. 33, will hold the arm 98 stationary, and with it the rack 93. At the same time, the salutation block is revolving with the bed 11; therefore, the salutation block, through the medium of the idler 92, the gear 89 and the rack 93, will be rotated on its axis, but it will be noted that due to the interposition of the idler 92 the salutation block will be rotated in an opposite direction to that heretofore described. This rotation will continue until the salutation block is rotated to the position illustrated in Fig. 34, with the face 85 in printing position. At this time the cam surface 130 will have engaged the roller 127. The pusher pin will therefore be moved to disengage the stop 101 from the arm 98 and the arm 98 being free the salutation block will not be further rotated, the cam 132, as heretofore described, locking the block in its printing position. It will be noted that one portion of the cam wheel 131 is of greater depth than any other portion. This is due to the fact that the stop 101, as it is arranged to engage either of the arms 97 or 98, must be shorter than the stops 100 and 102, so that when it is in its non-engaging position it will not engage either of the arms. Therefore, being shorter, it must have a greater forward movement in order to project into the path of the arms 97 and 98. To this end, therefore, I provide a deep portion of the cam surface so that the stop member may properly project into the path of the arms. However, when the cam surface 130 moves to a position to engage the roller 127, it operates the pusher pin sufficiently to move the stop 101 out of engagement with the arms.

We will now assume that after the salutation "Dear Madam" set up on the face 85 has been printed, the next plate will contain an address to a man; the salutation therefore printed should be "Dear Sir." Under these circumstances, the address plate would have the depressor 119 turned down, and as the plate passes over the rear end of the lever 115 the rear end of this lever will be depressed, permitting the trigger 111 to release the stop 102, whereupon the stop will be projected into the path of the arm 98, holding this arm against movement, and as the salutation block continues to revolve with the bed 11, the salutation block will be rotated in the same direction as described

in the preceding paragraph, and will eventually move to the position illustrated in Fig. 36 with the salutation face 82 in printing position.

As long as the arm 97 is not held against movement it continues to move until it reaches the position illustrated in Fig. 36. If, now, the next address plate should contain an address to a woman and the depressor 120 therefore be turned down, the stop 101 would be projected into the path of the arms, and as the arm 97 is now leading, it would be engaged by the stop and held. The holding of this arm 97 would rotate the salutation block, due to the engagement of the pinion 88 with the rack 90, until the face 85 were again in printing position.

If no salutation is desired to be printed, then the arms 97 and 98 may be separated manually to the position illustrated in Fig. 37 and the blank face 83 presented. It will, of course, be understood that after the salutation has once been changed, if all of the following plates are of the same character of address, the salutation block will be in no wise affected and it will continue to print the salutation to which it has been moved until a plate passes through having a different character of address set up thereon.

Paper feeding mechanism.—The impression receiving sheet is delivered to the printing mechanism in a proper time relation to the type plates, so that the imprint will be properly placed upon the sheet, by means of a paper feeding mechanism which is located at the intake side of the printing mechanism. This paper feeding mechanism, particularly shown in Figs. 5, 6 and 7, is mounted on the carriage 17 and comprises generally a paper receiving ledge or bar 135, a feeding or drawing roll 136 which is adapted to withdraw the sheets one by one from the ledge or bar and pass them down along a guide plate 137, and a set of stopping and releasing dogs 138 which co-operate with the feeding roll. These dogs are adapted to control the time of the feeding of the impression receiving sheet to the printing mechanism.

The feed roll is provided with a plurality of rubber bands 139 which are adapted to frictionally engage the paper and draw the same off the receiving ledge or bar 135. It is driven at the same speed as and in unison with the pressure roll 13 by a train of gears 140 mounted in the carriage. Like the pressure roll, it is removably secured in the frame by means of a centering pin 141, which centering pin is locked in position by a thumb screw 142.

An expandable and collapsible paper holding means is provided for supporting the paper in an inclined position upon the receiving ledge or bar 135 and this paper

115

120

125

130

holder comprises inclined double floors 143, upon which the pack of paper or envelopes or other impression receiving sheets is adapted to be placed on edge. Due to the 5 inclination of the floors the pack settles down on the ledge close to the feed roll. The edge of the feed bar 135 is adjacent the feed roll 136 and is provided with restraining and retarding devices 144 which prevent 10 the friction between the first and second sheets from withdrawing the second sheet while the first is being withdrawn by the drawing roll 136. When the first sheet of paper is withdrawn, however, it is held 15 against being fed into the machine by the stop dogs 138 until the printing mechanism is ready to receive the sheet. At the proper instant the dogs are retracted and permit the sheet to pass on down to the 20 printing mechanism in time to meet the type plate. These dogs project through openings in the guide plate 137 and are mounted at proper intervals on a transversely extending supporting bar 145 which extends the 25 width of the paper feeding mechanism and is adapted to reciprocate radially to and from the feed roll at stated periods. The dogs are operated by arms 146 to which they are connected and which are mounted or 30 carried upon a shaft 147 journaled in the carriage 17. For causing the intermittent action of the dogs 138, I provide a cam 148 integrally formed on the sleeve 55 and having a cam projection 149. This cam actuates 35 the dogs through an intermediate system of levers, one of which comprises an arm 150 pivotally mounted on the main frame and having a roller 151 adapted to be engaged by the cam projection 149 as the cam wheel rotates. This arm 150 comprises one arm of a bell crank lever, the other arm 152 of which carries a spring held detent 153 which engages the notched end of an arm 154 secured to the shaft 147. The arm 40 150 of the bell crank just described is normally maintained in position to be engaged by the projection 149 by means of a coiled spring 155, one end of which is connected to the arm 152 and the other end of which is 45 connected to the frame. It will be seen from the above lever mechanism that each time the cam projection 149 operates the bell crank arm, the dogs are retracted from out of the path of the paper to permit a sheet 50 to pass on to the printing mechanism.

The timing of the dogs 138, to control the time at which the sheet is delivered to the printing mechanism and thereby adjust the point on the sheet where the printing commences, is accomplished by moving the cam 148 to change the relative position of the projection 149 with respect to the type bed. It will be remembered that the sleeve 55, Fig. 10, on which the cam wheel 148 is 55 formed, is connected to the shaft 14 by the

two disks 63 and 64. By loosening the thumb nuts 67 the disks 63 and with it the sleeve 55 and the cam 148 may be rotated relatively to the shaft 14 and the type bed 11 to vary the relation of the cam projection 149 and type bed. 70

The skipping mechanism.—Occasions arise where it is not desirable to print letters for every one of the type plates which pass through the machine. Much time 75 would be wasted and the order, in which the type plates are arranged, changed by picking out the type plates for which no letters are desired to be printed. My machine is therefore so arranged that when a type plate 80 passes through the machine for which it is not desired to print a letter, the machine will be caused to skip; the impression mechanism being thrown out of impression position and no sheet being fed to the machine. 85

In order that the above may be accomplished, the forward end of the paper carriage 17 is movably supported (see Figs. 5 and 7). The points of support for the carriage are two adjustable spring-pressed pins 90 156 which project below the bottom of the carriage and rest on the frame of the machine, and are held in their projected position by coiled springs 157 interposed between the pins and closing screws 158 in the top of the spring receiving sockets formed in the carriage frame. The heads 159 of the pins form limit stops for the upward movement of the carriage. These spring-pressed pins 156 normally tend to separate the platen 13 from the type and type plate beds. The carriage, however, is locked down to hold the plates in pressure position by a pair of hooks 160, one located on each side of the carriage, which are engaged by a pair of 95 spring held triggers 161 pivotally mounted upon the end of a pair of arms 162. These arms in turn are pivotally mounted upon stud shafts 163 extending inwardly from the side members of the frame. Each of the 100 arms 162 is provided on its rear end with a bifurcated portion 164 which embraces a corresponding cam 165 mounted on the shaft 166. This locking mechanism not only 105 serves the function of permitting the printing mechanism to be thrown out of operation as hereinafter described, but also permits the carriage frame to be raised for the purpose of inspection of the parts beneath the same when desired. This may be accomplished by manually rocking the shaft 166 a complete half turn so that the cam 165 will depress the rear ends of the arms 162. This raises the front ends of the arms sufficiently to cause the projections 167 on the 110 triggers 161 to engage the adjustable stops 168 on the frame and throw the triggers out of engagement with the hooks 160. To rotate the shaft 166 manually, the shaft is provided on the exterior of the machine with a 115

120

triggers 161 to engage the adjustable stops 168 on the frame and throw the triggers out of engagement with the hooks 160. To rotate the shaft 166 manually, the shaft is provided on the exterior of the machine with a 130

crank 169, see Fig. 1, which is rotated in a counter-clockwise direction to unlock the carriage, the arm being held against movement in a clockwise direction by a stop 170 5 extending in its path from an adjustable plate 171. This plate is held in adjustment by a thumb screw 172 extending through a slot 173 in the plate. By means of the adjustable plate 171, the pressure of the platen 10 roll is controlled, it being readily seen that the arms 162 may have a slight up and down movement before the triggers 161 are unlocked and by varying this up and down movement the vertical position of the front 15 end of the carriage 17 and with it the pressure roll may be varied.

The front end of the carriage is automatically permitted to raise the platen 13 out of pressure position when a type plate 20 passes through the machine for which it is not desired to print a letter, by means of a mechanism set in motion by the passage of the type plate. A part of this mechanism, shown particularly in Figs. 17 to 23, 25 consists of a rocker arm 174 provided with a rack 175 adapted to engage a pinion 176 mounted on the shaft 166. This pinion is keyed on a hub 177 loosely mounted on the shaft 166 and this hub is provided with a 30 clutch member 178. The hub is hollow at the point where the clutch is formed, to admit the insertion of a small collar 179 pinned to the shaft which, together with the cam 165 prevents any lateral movement 35 of the pinion 176, at the same time permitting the pinion to freely rotate on the shaft. This pinion is adapted to be rotatably connected with the shaft 166 by means of a second clutching member 181 feathered on 40 the shaft.

The arm 174 at its end has a bifurcated portion 182, the arms of which are provided with rollers 183 adapted to embrace a cam 184 mounted on the shaft 14, so that as the 45 cam 184 rotates with the shaft 14, the arm 174 will be positively moved up and down, thereby rotating the pinion 176. The clutch member 181 has an annular slot 185 to receive the pins 186 projecting inwardly from 50 the embracing arms 187. These arms are mounted on a skeleton frame 188, which at its rear end is pivoted as at 189 between the brackets 190 extending laterally from the frame. One of the arms 187 is connected by 55 a link 191 and rod 192 with one arm 193 of a bell crank lever, and the opposite arm 194 of the bell crank lever is arranged to project into the path of the detent 153. The arm 193 is also connected by a coiled spring 60 195 with the side frame of the machine, which coiled spring is adapted to aid in overcoming the pull of a coiled spring 196 connected to one of the arms 187 and the frame of the machine. The frame 188 is 65 provided with a roller 197 adapted to be

engaged by a cam projection 198 formed on the side of a gear wheel 199 mounted on the shaft 200. This gear wheel is driven through an idler 201 adapted to mesh with a gear wheel 202 mounted on the shaft 14. 70 The idler 201 is mounted on a stud shaft 203 supported in a journal 204 carried on the frame of the machine. The link 191 is connected with one end of a lever 205 supported on a pivot 206 extending downwardly 75 from the bed of the machine. The free end of the latch 207 is provided with a shoulder 209 adapted to be engaged by the rear end of a trigger 210 pivoted to a boss 211 and having its front end bent transversely as 80 at 212. Also hingedly mounted on the pivot for the trigger are two depressor arms 213 and 214, the arms being slotted at 215 to fit over the pivot 216. By the provision of this slot, the arms are not only pivotally 85 mounted, but may have a slight longitudinal movement. The forward ends of the arms are provided with two notches 217 and 218 of different depths and are arranged to rest upon the cross member 212 of the trigger 90 210. When the arms are in inoperative position, the cross member 212 is in the notches 217 in the arms and both arms are below the level of the bed of the machine. If, however, either of the arms is raised and pulled 95 forward until the cross member 212 engages in the notches 218, the top of the arm will project through a suitable slot 219 to a tripping position.

Each type plate is provided with a depressor member 220 having fingers 221 and 100 222 which may be turned down to form depressors adapted to engage the tops of the arms 213 and 214. If the finger 222 is turned down it will engage the arm 214. If 105 the finger 221 is turned down it will engage the arm 213 when it is moved to its raised position. I have illustrated only two depressor arms, but it will be understood that any number may be used if desired and each 110 type plate may have a corresponding number of depressor fingers. Those type plates with the fingers turned down will be the type plates which pass through the machine without causing the machine to 115 print. This is particularly desirable where it is intended to write letters for only a portion of the type plates. We will take, for example, a mailing list for grocers. We will assume that this list is made up according to States and contains not only the names of wholesale grocers but of retail grocers. The plates having the addresses of the retail grocers thereon will have their stop fingers 222 turned down. We will now 120 assume that it is desired to send out a circular letter to the wholesale grocers only. In this event, the arm 214 will be raised and slid forward until the notch 218 engages the cross member 212. This will raise the arm 125 130

214 to a position where it will be engaged by the fingers 222 on the plates as they pass through the machine. At the same time, the arm 214 will not be affected by the passage 5 of the other plates. We will assume that the machine is running and that one of the plates having the finger 222 turned down passes through the machine on its way to the printing portion of the machine. First it 10 must be understood that as the cam 184 rotates it positively rocks the arm 174 first upwardly and then downwardly, thereby rotating the pinion 176, first in one direction and then in the other. It must also be understood that as the gear wheel 199 rotates, 15 the cam member 198 on each rotation of the wheel will engage the roller 197, thereby moving the frame 188 inwardly against the tension of the spring 196. It will be noted 20 that the inward movement of the frame 188 will move the rear end of the lever 205 outwardly, thereby causing the shoulder 209 to move away from the trigger 210, leaving the trigger free to move unimpeded by any 25 frictional engagement between it and the shoulder 209. This movement is provided for as the weight of the type plates is not great and the frictional engagement, increased by the tension of the spring 196 30 would tend to so lock the trigger 210 with the latch 207 that the front end of the trigger could not readily be depressed. With this understanding, and assuming that a type plate, as before mentioned, is passing 35 on its way to the printing mechanism with its finger 222 turned down, when the plate arrives in a position on the bed above the arm 214 it will depress the arm, raising the rear end of the trigger 210 so that the shoulder 209 may pass beneath the same when 40 the roller 197 passes off the cam 198 and the clutch member 181 moves into engagement with the clutch member 178. The pinion 176 is now locked to the shaft 166. The upward movement of the arm 174, caused by 45 the rotation of the cam 184, therefore rotates the shaft 166, rotating the cams 165 to depress the rear end of the arms 162 and permit the front end of the frame 17, and with it the platen 13, to raise under the influence of the spring pins 156 to a non-pressure position so that the type plate will pass through the machine and the type bed 50 11 rotate, without making an impression. 55 The same movement which connects the clutch members 178 and 181 will, through the rod 192, rock the arm 194 into engagement with the detent 153, moving the detent out of the path of the arm 154 so that 60 as the detent moves upwardly the stop dogs 138 will not be moved out of the path of the paper, and the sheet of paper will be held from passing to the printing mechanism. By the time the type plate has passed 65 through the printing mechanism, the cam 184 will have rotated to move the arm 174 downwardly again, which will rotate the pinion 176 in an opposite direction from that heretofore described, and rotate with it the shaft 166 and the cams 165 to cause 70 the rear end of the arms 162 to be raised, thereby drawing the front end of the carriage, and with it the platen 13, downwardly again to move the platen into an impression position. It will of course be understood that during the operation above described the cams will never be rotated sufficiently far to entirely disconnect the triggers 161 from the hooks 160. As soon as the platen has been drawn down to an 75 impression position, the cam 198 again engages the roller 197 and disconnects the clutch members 178 and 181, at the same time rocking the rear end of the lever 205 to move the catch from beneath the trigger 80 210, permitting the trigger to drop in front of the shoulder 209 so that when the roller 197 passes off the cam 198 the clutch members will not engage. The same movement of the lever 205 rocks the arm 194, out of 85 the path of the detent 153, so that the detent will be in a position to engage the arm 154 and cause the stop dogs 138 to be moved out of the path of the sheet of paper when 90 the next type plate passes through the machine, and a sheet of paper will be delivered to the machine to receive an impression. 95

As has been before mentioned, the platen roll 13 is driven by a direct gear connection with the shaft 14. This gear connection, as 100 shown in Figs. 8 and 24, comprises a gear wheel 223 mounted on the shaft 14 which meshes with a pinion 224 mounted on a stub shaft arranged in a gear casing 225. Meshing with the pinion 224 is a pinion 226 also 105 mounted on a stub shaft arranged in said casing. This same stub shaft has mounted thereon a gear 227 which in turn meshes with a pinion 228 mounted on a shaft 228' and keyed to the hub of the clutch member 110 228''. One end of the shaft 21 is provided with a second clutch member 229. These two clutch members are provided with a pair each of inwardly projecting teeth 230 which, it will be noted, are so arranged that 115 while they will connect the shafts 21 and 228' for driving purposes, the shaft 21 may be readily separated by raising the carriage 17. This shaft 21 is also provided with one of the train of gears 140, through which the 120 drawing roll 136 is driven.

Inking ribbon mechanism.—The impression made by my machine is made through an inking ribbon in order that the letter printed may bear a resemblance to a type-written letter. The type being metal type and having the same characteristics as the type of the typewriter, and the impression being made through a ribbon in the same manner as is the impression made by a type- 125 130

writer, the resultant work of my machine so nearly resembles the work of a typewriter that it cannot be distinguished from that of a typewriter. To the end that the impression may be made through an inking ribbon, I provide a ribbon 231. This ribbon is of sufficient width to overlie not only the type bed 11 but also that portion of the type plate bed 12 over which the portion of the type plate bearing the address passes, and also that portion of the drum 74 which carries the dating mechanism. This ribbon is arranged to pass between the platen 13 and the beds of the printing mechanism. It is wound upon two ribbon reels 232 and 233, termed respectively for convenience the pay-out reel and the take-up reel. Since the ribbon is under compression in the printing mechanism during the printing operation, it is desirable that there be no relative movement between the face of the type and the paper, or between the face of the type and the ribbon; otherwise the impression would be blurred and the ribbon torn. Therefore, I feed the ribbon during the printing operation in the same direction as the paper moves. This is accomplished by rotating the pay-out reel during the impression movement of the parts so that the ribbon will feed through the printing mechanism at the same speed at which the printing mechanism is rotated. However, as the constant feeding forward of the ribbon in passing a large number of type plates through the machine would necessitate an extremely long ribbon, I provide a mechanism which rewinds or retracts the ribbon after the printing operation takes place. This mechanism is so arranged that it may retract a greater length of ribbon than is fed forward, or it may retract a lesser length of ribbon than is fed forward, depending upon the roll from which the ribbon is feeding. Starting, say, with all the ribbon wound on the pay-out reel 232, each retractive movement of the ribbon is of less length than the forward movement, so that eventually the entire ribbon will be wound on the take-up reel 233. If the entire length of the ribbon is wound on the take-up reel, the retractive movement of the ribbon is greater than the forward movement, so that eventually the ribbon will again be wound back on the pay-out reel. The mechanism which I have provided for accomplishing this movement of the ribbon is so designed that it will automatically change the length of ribbon retracted when the respective reels are filled. For the purpose of actuating the pay-out reel 232, I provide two trains of gears 234 and 235, Figs. 4 and 7, suitably journaled in a housing or gear box 236 secured to the main frame. These gears are independent of each other and rotate the pay-out reel 232 in opposite directions. They are thrown into op-

eration by means of a clutch 237 mounted on a shaft 238 which is driven from the rear shaft 71 of the conveying mechanism by a sprocket chain 239. The clutch 237 is operated at proper time intervals by cams 240 through a bell crank lever 241 and link 242, Fig. 3. The cams 240 are slidably mounted upon the shaft 200 and derive their movement from the same gear 202 which drives the gear 199. The cams bear a definite time relation to the printing mechanism and are shifted into engagement with one arm of the bell crank lever 241 by means of a lever 243 which is adapted to be actuated at the end of a series of intermediate movements of the ribbon in either direction by a snap-over device 244 actuated by a traveling nut 245 which moves backward and forward on a threaded shaft 246. This shaft is associated with the gear trains of the reel mechanism and has a rotary movement which is a counterpart of the reciprocating progressive movement of the ribbon.

The forward or take-up reel 233 is located in the front end of the frame, which portion of the frame is formed as a housing to protect the ribbon and various other parts mounted therein. Extending inwardly from the side of the frame is a boss 247 in which is mounted a stub shaft 248 having secured on its inner end a sprocket wheel 249 over which is adapted to pass a driving sprocket chain 250 connected at its rear to the sprocket 29 heretofore described, and mounted upon the main shaft 14 so that the sprocket wheel 249 partakes of the constant speed of the main shaft. The inner end of the shaft 248 is provided with a friction member 251, preferably in the form of a truncated cone, which is adapted to engage in a correspondingly shaped socket 252 formed in a socket member secured upon one end of the roll 233 and forming a friction driving connection between the roll and the sprocket 249. This friction driving connection is sufficient to rotate the reel when the ribbon is paid out, but it is not so great but that it may be overcome by the relatively stronger powered gear mechanism of the pay-out reel when the ribbon is retracted. The take up reel 233 is removably held in position at its opposite end by means of a spring pressed centering pin 253 which may be locked in position by a thumb screw 254.

In order that the ribbon may be rewound on the pay-out reel 232 at any time desired, I have provided a mechanism for operating the clutch 237 by hand and independently of the operating mechanism. The link 242 is divided into two sections, each section carrying a fixed block 255 in which the end of the other section reciprocates. On the section 256 and between the blocks is arranged a spiral spring 257. This arrangement constitutes an elastic connection between the

clutch mechanism for actuating the clutch, and permits the clutch 237 to be thrown manually by a simple pressure upon the end of a lever 258 pivoted at 259 to the frame 5 and connected at 260 with the section 256 of the link.

Sheet delivery mechanism.—After the impression receiving sheet has received its imprint it is received by a paper delivering 10 mechanism which delivers the same to a suitable tray. This paper delivering mechanism is so constructed that when the paper is first delivered to the printing mechanism a portion of the paper delivering mechanism 15 is adapted to receive the edge of the sheet to prevent the same from coming in contact with the inking ribbon. As the printing operation progresses, the paper delivering mechanism is retracted so as to keep out of 20 the path of the printing mechanism and eventually has its front end raised to properly clear the plate delivery chute. The paper delivery mechanism, Figs. 5, 6, 15 and 42, is comprised of two frames 261 and 262. 25 The frame 261 is relatively stationary and is provided with suitable conveyers for receiving the sheet as it comes from the frame 262 and delivers it to a paper receiving device. The frame 262 is adapted to reciprocate and 30 its forward end is adapted to project into the path of the paper as it is fed into the machine, to receive the edge of the paper and prevent it from coming in contact with the printing ribbon. The frame 261 comprises 35 a pair of skeleton side members 263 hingedly mounted on the bearing members 264 secured between the sides of the frame. At the front end of the frame and between the two side members 263 is arranged a delivery roller 265 which is secured to shafts 266 in the journal members 264. Secured on the outer end of one of the shafts 266 is a gear wheel 267 which is connected by a driving train 268, Fig. 1, with a gear 269 40 mounted on the shaft 248 on the take-up ribbon reel, whereby the delivering roller 265 derives its movement from the main shaft. The two side arms 263 are connected together by a top platform 270 and at their 45 outer ends have secured between them a shaft 271 carrying a plurality of spools 272 over which and the roll 265 a plurality of conveying webs 273 pass. The front end of the frame 261 is supported upon the sides of 50 the main frame of the machine. Arranged beneath the platform 270 and between the side members 263 is the second frame section 262. This frame section comprises a skeleton portion 274 which is provided with a 55 forwardly extending downwardly curved paper receiving projection 275. This paper receiving section is slotted as at 276 to permit the web rolls 272 which are arranged beneath the same to project therethrough. 60 65 The frame 262 is adapted to run on pairs of 70 75 80 85 90 95 100 105 110 115 120 125 130 rollers 278 and 279 operating in slotted guides 280 formed in the side members 263. The rear rollers are supported upon stub shafts 281 which extend from a portion of the frame 262, and the front rollers are 70 mounted on pins 282 also extending laterally from the frame. The pins 282, however, are extended to fit in notches 283 formed in reciprocating bars 284 mounted in guideways 285 on the side frames of the machine.

Due to the mounting of the frame 262 as heretofore described, it will be seen that this frame may be moved backward and forward independently of the frame 261. At the same time, due to the fact that the pins 282 fit in notches in the reciprocating bars 284, the entire paper delivering mechanism may be swung upwardly about the center of the roll 265 as a pivot and permit access to and inspection of the forward interior part of the machine, the frame 262 being connected to the side members 263 by the rollers 278 and 279 in the slots 280. The reciprocating side bars 284, as before stated, impart a reciprocating movement to the frame section 262, and these side members receive their movement from a segmental gear 285 mounted on a shaft 286 and adapted to mesh with the racks 287 formed on the under side of the bars. As before stated, the forward end of the paper delivering mechanism at the same time it moves backward is given a slight upward movement. This upward movement is imparted thereto by cam members 288 also mounted upon the shaft 286 and practically coincident with the segmental gears 285. The top portions of these cam members are flattened as at 289 to provide sliding portions on the cams on which the frame section 262 slides on its backward movement during the period that it is raised by the cams. The cams 288 and the segmental gears 285 receive a reciprocating movement from the shaft 286 which in turn derives its movement from a link 290 connected to one of the arms supporting the cams 288, and having its other end connected to an arm 291 pivotally connected to the frame and provided with a bifurcated portion 292 having rollers 293 on its bifurcated ends adapted to be engaged by a cam 294 on the shaft 14.

A pressure roll 296 is arranged above the conveyer belts 273 to bear slightly upon the 120 paper and prevent it from being blown or otherwise displaced from the conveyer belts as it is received from the machine. This pressure roll is mounted between a pair of arms 297 hingedly supported upon lugs 298 125 extending upwardly from the platform 270. These arms are connected by a cross member 299, and on the under side of this cross member I place bunches of tinsel or like material 300 which effectually destroy any static elec-

tricity imparted to the paper during its printing operation and which would tend to cause the paper to curl or the sheets of paper to stick to one another.

5 In operation, the paper delivering mechanism, it being remembered that the conveyer tapes 273 are continuously operating, is in the position illustrated in Fig. 6. As soon as the edge of the sheet of paper strikes the 10 projecting paper receiving portion 275, the cam 294 is so timed that the paper receiving portion 275 immediately commences to move backward, this backward movement being at the same speed as the forward movement of 15 an impression plate, so that the movable section of the paper delivering mechanism moves out of the path of the type plate, at the same time supporting the front edge of the paper and preventing it from coming in 20 contact with the inking ribbon. At the same time that the movable section of the paper deliverer is given this rearward movement, it is given a slightly upward movement by the cams 268, which it will be remembered 25 are coincident with the segmental gear 285, so that while the front end of the paper delivering mechanism is moving backward, it is being slightly raised. This upward movement, it will be understood of course, is not 30 very great but is just sufficient to give the paper a slight curl upward and at the same time clear all of the paper, except that immediate portion which is receiving an impression, from the inking ribbon. The movable section 262 of the paper delivering mechanism continues in its rearward movement until the front edge of the paper is 35 engaged between the roller 296 and the conveyer tapes 273, when the sheet of paper 40 will be taken up by the conveyer tapes and finally delivered over the delivery roller 265 to any proper receptacle for receiving the same.

Plate packer.—After the plates have 45 passed through the printing mechanism, they are delivered to a plate receiving drawer 301 which is removably supported between the side members of the frame on the spacer beams 4 and has one end projecting 50 beneath the plate delivery chute 302 which guides the plates as they pass from the printing mechanism to the plate receiving drawer. As each plate drops into the drawer, it must be moved backward out 55 of the path of the next succeeding plate, and to this end I provide a plate packer (see particularly Figs. 16 and 22) which comprises a pair of plate engaging jaws 303 adapted to be projected over the sides of 60 the drawer and then moved rearwardly to move the plate rearwardly. The jaws, after the plate has been moved rearwardly, again move forwardly and outwardly to be in a position to engage the next succeeding plate. 65 These jaws or packers are mounted upon the

forward end of a pair of jaw carrying arms 304 pivoted at 305 to lateral projecting bosses 306 on reciprocating arms 307. Interposed between the forward ends of the arms and depending pins 308 on the jaw carrying arms are coiled springs 309 which serve to keep the forward ends of the arms 304 in their outward position so that the jaws will normally be out of the path of the dropping plates. As, however, the reciprocating arms 70 307 are moved rearwardly, the rollers 310 upon the rear end of the arms 304 engage cam surfaces 311 stationarily mounted on the side frames of the machine, so that the forward ends of the arms 304 are caused to 75 move inwardly whereby the packer jaws 303 receive an inward and rearward movement at the same time. Of course it is understood that as the arms 307 move forward again, under the influence of the coil 80 springs 309, the packer jaws will be given an outward movement. The necessary reciprocating movement is imparted to the arms 307 through a connection of one of the arms with an oscillating arm 312 which is 85 pivoted at 313 to the frame and is provided at its upper end with a bifurcated portion 314, the ends of which are provided with rollers 315 and are adapted to span a cam 316 mounted upon the shaft 14. The rear 90 ends of the arms 307 are connected by links 317 with cranks 318 mounted upon a shaft 319 extending beneath the drawer support so that the movement imparted by the arm 312 will be directly imparted to both of the 95 reciprocating arms 307. 100

While I have shown and described one embodiment of my invention, it will be understood that various changes and modifications may be made therein without departing from the spirit of my invention as set forth in the appended claims. It will also be understood that various features of my invention are applicable not only to a combined printing and addressing machine, 110 but may be used in an addressing machine alone. 115

Having thus described my invention, what I claim as new and desire to secure by Letters Patent is

1. In a printing and addressing machine, the combination with a type bed, of an independently movable type plate bed, means for delivering type plates to said plate bed, a platen coöperating with said beds for making an impression and arranged to move the plate bed at the same surface speed as the surface speed of the type bed during the passage of a plate beneath the platen. 120

2. In a printing and addressing machine, 125 the combination with a type bed, of a type plate bed mounted independently of said type bed and movable independently thereof, means for delivering type plates to said plate bed, a platen coöperating with said 130

beds for making an impression and arranged to move the plate bed at the same surface speed as the surface speed of the type bed during the passage of a type plate beneath 5 the platen.

3. In a printing and addressing machine, the combination with a type bed, of a type plate bed mounted to move independently of the type bed, means for delivering type 10 plates to the plate bed, a platen coöperating with said beds for making an impression and arranged to move the plate bed at the same surface speed as the speed of the type bed during the passage of a type plate beneath 15 the platen.

4. In a printing and addressing machine, the combination with a type bed, of an independently and freely movable type plate bed, means for delivering type plates to the 20 plate bed, a platen coöperating with said beds for making an impression and arranged to move the plate bed at the same speed as the surface speed of the type bed during the passage of a type plate beneath the platen.

25 5. In a printing and addressing machine, the combination with a type bed, of an independently movable type plate bed, means for delivering type plates to the plate bed, and a platen coöperating with said beds for 30 making an impression, said plate bed being arranged to be moved by the passage of a type plate thereover at the same surface speed as the surface speed of the type bed.

6. In a printing and addressing machine, 35 the combination with a rotary type bed, of a rotary, coaxial type plate bed rotatable independently of the type bed, means for delivering type plates to said plate bed, a rotary platen coöperating with said beds for 40 making an impression and arranged to rotate said type plate bed at the same peripheral speed as the peripheral speed of the type bed during the passage of a type plate beneath the platen.

45 7. In a printing and addressing machine, the combination with a rotary type bed, of a rotary, coaxial, independently rotatable type plate bed of smaller diameter than the type bed, means for delivering type plates 50 to said plate bed, a rotary platen coöperating with said beds for making an impression and arranged to rotate said plate bed at the same peripheral speed as the peripheral speed of the type bed, during the passage 55 of a type plate beneath said platen.

8. In a printing and addressing machine, the combination with a rotary type bed, of a rotary, coaxial, independently rotatable type plate bed, means for delivering type plates 60 to said plate bed, a rotary platen coöperating with said beds for making an impression, said type plate bed being of smaller diameter than the type bed and being adapted to be rotated by the passage of a type

plate thereover at the same peripheral speed 65 as the peripheral speed of the type bed.

9. In a printing and addressing machine, the combination with a rotary type bed, of a rotary type plate bed co-axial with the type bed and mounted to freely rotate, said 70 beds being of different diameters, the difference in the diameters of the beds being the thickness of a type plate, whereby when a type plate is passing over the type plate bed its printing surface will be coincident 75 with the printing surface of the type bed, said type plate bed being arranged to be rotated by the passage of a type plate thereover at the same peripheral speed as the peripheral speed of the type bed. 80

10. In a printing and addressing machine, the combination with a rotary type bed, of a rotary type plate bed rotatable independently of the type bed and of smaller diameter, the difference in the diameters of 85 the type bed and plate bed being equal to the thickness of a type plate, whereby the impression surface of the type plate as it passes over the type plate bed will be coincident with the impression surface of the 90 type bed, a rotary platen coöperating with said beds for making an impression and arranged to rotate the plate bed at the same peripheral speed as the peripheral speed of the type bed. 95

11. In a machine of the character described, the combination with a movable type bed, of a type plate bed, means for delivering type plates to said plate bed, a platen coöperating with said beds for making an impression and arranged to move the plate bed during the passage of a plate beneath the platen at the same surface speed as the speed of the type bed, and means for automatically feeding impression receiving 100 sheets one at a time beneath said platen.

12. In a printing and addressing machine, the combination with a movable type bed, of a type plate bed mounted independently of said type bed, means for delivering type 110 plates to said bed, a platen coöperating with said beds for making an impression and arranged to move the plate bed during the passage of a type plate beneath the platen at the same surface speed as the surface 115 speed of the type bed, and means for automatically feeding impression receiving sheets one at a time beneath said platen.

13. In a printing and addressing machine, the combination with a movable type bed, of 120 a type plate bed mounted to move independently of the type bed, means for delivering type plates to the plate bed, an impression platen coöperating with said beds for making an impression and arranged to move the 125 plate bed during the passage of a type plate beneath the platen at the same surface speed as the speed of the type bed, and means for

automatically feeding impression receiving sheets one at a time beneath said platen.

14. In a printing and addressing machine, the combination with a movable type bed, of a freely movable type plate bed, means for delivering type plates to said plate bed, a platen coöperating with said beds for making an impression and arranged to move the plate bed during the passage of a type plate 10 beneath the platen, at the same speed as the surface speed of the type bed, and means for automatically feeding impression receiving sheets one at a time beneath said platen.

15. In a printing and addressing machine, the combination with a movable type bed, of an independently movable type plate bed, means for delivering type plates to the plate bed, an impression platen coöperating with said beds for making an impression, said 15 plate bed being arranged to be moved by the passage of a type plate thereover at the same surface speed as the surface speed of the type bed, and means for automatically feeding impression receiving sheets one at a time 20 between said beds and platen.

16. In a printing and addressing machine, the combination with a rotary bed, of an independently rotatable type plate bed, means for delivering type plates to said 25 plate bed, a rotary platen coöperating with said beds for making an impression, said platen being arranged to rotate said plate bed at the same speed as the peripheral speed of the type bed, and means for automatically 30 feeding impression receiving sheets one at a time between said platen and beds.

17. In a printing and addressing machine, the combination with a rotary bed, of an independently rotatable type plate bed of small diameter than the type bed, a 35 rotary platen coöperating with said beds for making an impression and arranged to rotate said plate bed at the same peripheral speed as the peripheral speed of the type bed, and means for automatically 40 feeding impression receiving sheets between said platen and beds.

18. In a printing and addressing machine, the combination with a rotary bed, of an independently rotatable type plate bed, means for delivering type plates there- 45 to, a rotary platen coöperating with said beds for making an impression, said plate bed being of smaller diameter than the type bed and being adapted to be rotated by the passage of a type plate thereover at the same peripheral speed as the peripheral speed of the type bed, and means for automatically 50 feeding impression receiving sheets one at a time between said platen and beds.

19. In a printing and addressing machine, the combination with a rotary type bed, of a rotary type plate bed mounted to

freely and independently rotate and co- 65 axial with the type bed, said beds being of different diameters, the difference in the diameters of the beds being the thickness of a type plate, whereby when a type plate is passing over the type plate bed its printing surface will be coincident with the printing surface of the type bed, said type plate bed being arranged to be rotated by the passage of a type plate thereover at the same peripheral speed as the speed of the 70 type bed, a rotary platen coöperating with said beds for making an impression, and means for automatically feeding impression receiving sheets one at a time between said platen and beds. 75

20. In a printing and addressing machine, the combination with a rotary type bed, of a rotary type plate bed movable independently of the type bed and of smaller diameter, the difference in the diameters of the type bed and plate bed being equal to the thickness of a type plate, whereby the impression surface of the type plate as it passes over the plate bed will be coincident with the impression surface of the 80 type bed, a rotary platen coöperating with said beds for making an impression and arranged to rotate the plate bed at the same peripheral speed as the peripheral speed of the type bed, and means for automatically 85 feeding impression receiving sheets one at a time between said platen and beds. 90

21. In a printing and addressing machine, the combination with a type bed, of an independently movable type plate bed, means for delivering type plates to said 95 plate bed, a platen coöperating with said beds for making an impression and arranged to move the plate bed at the same surface speed as the surface speed of the type bed during the passage of a type plate 100 beneath the platen, and an inking ribbon interposed between said beds and platen.

22. In a printing and addressing machine, the combination with a type bed, of a type plate bed mounted independently of said type bed, means for delivering type plates to said plate bed, a platen coöperating with said beds for making an impression and arranged to move the plate bed at the same 110 surface speed as the surface speed of the type bed during the passage of a type plate beneath the platen, and an inking ribbon interposed between said platen and beds. 115

23. In a printing and addressing machine, the combination with a type bed, of a type plate bed mounted to move independently of said type bed, means for delivering type plates to said plate bed, a platen coöperating with said beds for making an impression and arranged to move the plate bed at the same surface speed as the surface speed of the type bed during the 120 125

passage of a type plate beneath the platen, and an inking ribbon interposed between said beds and platen.

24. In a printing and addressing machine, the combination with a type bed, of a freely movable type plate bed, means for delivering type plates to the plate bed, a platen coöperating with said beds for making an impression and arranged to move the plate bed at the same speed as the surface speed of the type bed during the passage of a type plate beneath the platen, and an inking ribbon interposed between said platen and beds.

25. In a printing and addressing machine, the combination with a type bed, of a type plate bed, means for delivering type plates to the plate bed, a platen coöperating with said beds for making an impression, said plate bed being arranged to be moved by the passage of a type plate thereover at the same surface speed as the surface speed of the type bed, and an inking ribbon interposed between said platen and beds.

26. In a printing and addressing machine, the combination with a rotary type bed, of a rotary type plate bed, means for delivering type plates to the plate bed, a rotary platen coöperating with said beds for making an impression, said platen being arranged to rotate said plate bed at the same peripheral speed as the peripheral speed of the type bed, and an inking ribbon interposed between said platen and beds and arranged to move during the printing operation synchronously with said platen and beds.

27. In a printing and addressing machine, the combination with a rotary type bed, of a rotary type plate bed of smaller diameter than the type bed, means for delivering type plates to said plate bed, a rotary platen coöperating with said beds for making an impression and arranged to rotate said type plate bed at the same peripheral speed as the peripheral speed of the type bed during the passage of a type plate beneath the platen, and an inking ribbon interposed between said beds and platen and arranged to move forward during the printing operation at the same speed as the rotary speed of the beds.

28. In a printing and addressing machine, the combination with a rotary type bed, of a rotary type plate bed, means for delivering type plates to said plate bed, a rotary platen coöperating with said beds for making an impression, said plate bed being of smaller diameter than the type bed and adapted to be rotated by the passage of a type plate thereover at the same peripheral speed as the peripheral speed of the type bed, and an inking ribbon interposed between said beds and platen and arranged to move forward during the printing operation

at the same speed as the rotary speed of said beds.

29. In a printing and addressing machine, the combination with a rotary type bed, of a rotary type plate bed co-axial therewith and mounted to freely rotate, said beds being of different diameters, the difference in the diameters of the beds being the thickness of a type plate, whereby when the type plate is passed over the plate bed its printing surface will be coincident with the printing surface of the type bed, said type plate bed being arranged to be rotated by the passage of a type plate thereover at the same peripheral speed as the peripheral speed of the type bed, and an inking ribbon interposed between said beds and platen and arranged to move forward during the printing operation at the same speed as the rotary speed of the beds.

30. In a machine of the character described, the combination with a rotary type bed, of a rotary type plate bed movable independently of the type bed and of smaller diameter, the difference in the diameters of the beds being equal to the thickness of a type plate, whereby the impression surface of the type plate as it passes over the type plate bed will be co-incident with the impression surface of the type bed, a rotary platen coöperating with said beds for making an impression and arranged to rotate the type plate bed at the same peripheral speed as the peripheral speed of the type bed, and an inking ribbon interposed between said platen and beds and arranged to move forward during the printing operation at the same speed as the rotary speed of the beds.

31. In a printing and addressing machine, the combination with printing mechanism comprising a type bed, a type plate bed and platen, of means for delivering type plates to said type plate bed, said type plate bed being moved by said platen at the same surface speed as the surface speed of the type bed during the passage of a type plate beneath said platen, an inking ribbon interposed between said platen and beds, and means for automatically feeding impression receiving sheets, one at a time to said printing mechanism and between said ribbon and platen.

32. In a printing and addressing machine, the combination with a printing mechanism comprising a type bed, a type plate bed mounted independently of said type bed, and a platen, of means for delivering type plates to said plate bed, said platen being arranged to move the plate bed at the same surface speed as the surface speed of the type bed during the passage of a type plate beneath the platen, an inking ribbon interposed between said beds and platen, and means for automatically delivering impres-

sion receiving sheets one at a time to said printing mechanism and between said inking ribbon and platen.

33. In a printing and addressing machine, 5 the combination with a printing mechanism comprising a type bed, a type plate bed movable independently of said type bed, and a platen, of means for delivering type plates to said plate bed, said platen being arranged 10 to move the plate bed at the same surface speed as the speed of the type bed during the passage of a type plate beneath the platen, an inking ribbon interposed between said beds and platen, and means for automatically feeding impression receiving sheets one at a time to said printing mechanism and between said ribbon and platen.

34. In a printing and addressing machine, 20 the combination with a printing mechanism comprising a type bed, a freely movable type plate bed, and a platen, of means for delivering type plates to said plate bed, said platen being arranged to move the type plate bed at the same surface speed as the 25 surface speed of the type bed during the passage of a type plate beneath the platen, an inking ribbon interposed between said platen and beds and means for automatically delivering impression receiving sheets one at 30 a time to said printing mechanism and between said platen and ribbon.

35. In a printing and addressing machine, 35 the combination with a printing mechanism comprising a type bed, a type plate bed, and a platen, of means for delivering type plates to said type plate bed, said type plate bed being arranged to be moved by the passage of a type plate thereover at the same surface speed as the surface speed of the type bed, 40 an inking ribbon interposed between the beds and platen, and means for automatically feeding impression receiving sheets one at a time to said printing mechanism and between said ribbon and platen.

36. In a printing and addressing machine, 45 the combination with a printing mechanism comprising a rotary bed, a rotary type plate bed, and a platen, of means for delivering type plates to said plate bed, said platen 50 being arranged to rotate said type plate bed at the same peripheral speed as the peripheral speed of the type bed, an inking ribbon interposed between said platen and beds, and means for automatically feeding impression 55 receiving sheets one at a time to said printing mechanism and between said ribbon and platen.

37. In a printing and addressing machine, 60 the combination with a printing mechanism comprising a rotary type bed, a rotary type plate bed of smaller diameter than the type bed, and a platen, of means for delivering type plates to the plate bed, said platen being arranged to rotate said plate bed at the same 65 peripheral speed as the peripheral speed of

the type bed, an inking ribbon interposed between said beds and platen, and means for automatically delivering impression receiving sheets one at a time to said printing mechanism and between said ribbon and platen. 70

38. In a printing and addressing machine, the combination with a printing mechanism comprising a rotary type bed, a rotary type plate bed, and a platen, of means for delivering type plates to said plate bed, said type plate bed being of smaller diameter than the type bed and being adapted to be rotated by the passage of a type plate thereover at the same peripheral speed as the peripheral 75 speed of the type bed, an inking ribbon interposed between said beds and platen, and means for automatically delivering impression receiving sheets one at a time to said printing mechanism and between said ribbon 80 and platen.

39. In a printing and addressing machine, the combination with a printing mechanism comprising a rotary type bed, a rotary type plate bed co-axial with said type bed and 90 mounted to freely rotate, and a platen, said beds being of different diameters, the difference in the diameters of the beds being the thickness of a type plate whereby when a type plate is passed over the plate bed its 95 printing surface will be coincident with the printing surface of the type bed, said type plate bed being arranged to be rotated by the passage of a type plate thereover at the same peripheral speed as the peripheral 100 speed of the type bed, of an inking ribbon interposed between said beds and platen and means for automatically feeding impression receiving sheets one at a time to said printing mechanism and between said ribbon and 105 platen.

40. In a machine of the character described, the combination with a printing mechanism comprising a rotary type bed, a rotary type plate bed movable independently of the type bed and of smaller diameter, the difference in the diameters of the type bed and type plate bed being equal to the thickness of a type plate whereby the impression surface of the type plate will be 110 coincident with the impression surface of the type bed, and a rotary platen co-operating with said beds for making an impression and arranged to rotate the type plate bed at the same peripheral speed as the peripheral speed of the type bed, of an inking ribbon interposed between said beds and platen 115 and means for feeding impression receiving sheets one at a time to said printing mechanism and between said ribbon and platen. 120

41. In a printing and addressing machine, the combination with a rotary type bed, of a rotary type plate bed, means for delivering type plates to said plate bed, a rotary platen co-operating with said beds for mak- 125 130

ing an impression, said platen being arranged to rotate said plate bed at the same peripheral speed as the peripheral speed of the type bed, an inking ribbon interposed between said beds and platen and arranged to have a forward and retractive movement, said forward movement taking place during the printing operation.

42. In a printing and addressing machine, 10 the combination with a rotary type bed, a rotary type plate bed of smaller diameter than the type bed, means for delivering type plates thereto, a rotary platen coöperating with said beds for making an impression and arranged to rotate said type plate bed at the same peripheral speed as the peripheral speed of the type bed, and an inking ribbon interposed between said beds and platen and arranged to have a forward 15 and retractive movement, said forward movement taking place during the printing operation.

43. In a printing and addressing machine, the combination with a rotary bed, of a rotary type plate bed, means for delivering type plates to said plate bed, a rotary platen coöperating with said beds for making an impression, said plate bed being of smaller diameter than the type bed and adapted to 20 be rotated by the passage of a type plate thereover at the same peripheral speed as the peripheral speed of the type bed, and an inking ribbon interposed between said beds and platen and arranged to have a forward 25 and retractive movement, said forward movement taking place during the printing operation.

44. In a printing and addressing machine, the combination with a rotary type bed, of 20 a rotary type plate bed co-axial with said type bed and mounted to freely rotate, said beds being of different diameters, the difference in the diameters being the thickness of a type plate, whereby when a type plate 25 is passed over the plate bed its printing surface will be coincident with the printing surface of the type bed, said plate bed being arranged to be rotated by the passage of the type plate thereover at the same peripheral speed as the peripheral speed of 30 the type bed, a rotary platen coöperating with said beds for making an impression, and an inking ribbon between said beds and platen and arranged to have a forward and 35 retractive movement, said forward movement taking place during the printing operation.

45. In a printing and addressing machine, the combination with a rotary type bed, 40 of a rotary type plate bed rotatable independently of the type bed and of smaller diameter, the difference in the diameters of the beds being equal to the thickness of a type plate whereby the impression surface 45 of the type plate as it passes over the plate

bed will be coincident with the impression surface of the type bed, a rotary platen coöperating with said beds for making an impression and arranged to rotate the type plate bed at the same peripheral speed as the peripheral speed of the type bed, and an inking ribbon interposed between said beds and platen and arranged to have a forward and retractive movement, said forward movement taking place during the printing operation.

46. In a machine of the character described, the combination with a type bed, of a type plate bed movable independently thereof, a platen coöperating with said beds 80 and arranged to move said type plate bed upon the passage of a type plate thereover, and means for locking said type bed against movement and in non-printing position.

47. In a machine of the character described, the combination with a movable type bed, of a type plate bed movable independently of said type bed, means for feeding type plates to said plate bed, a rotary platen arranged to move said type plate 90 bed upon the passage of a type plate thereover, and means for locking said type bed against movement and in a non-printing position.

48. In a machine of the character described, the combination with a rotary type bed, of a rotary type plate bed, rotatable independently of the type bed, means for feeding type plates to said plate bed, and a rotary platen coöperating with said beds for 100 making an impression and arranged to rotate said type plate bed during the passage of a type plate thereover, and means for locking said type bed against rotation and in non-printing position.

49. In a machine of the character described, the combination with a rotatable type bed, of means for printing a separate address on each letter printed by said type bed, a salutation member rotatable with said type bed and carrying a plurality of salutations, and means for causing said salutation device to automatically present any one of the salutations carried thereby to printing position.

50. In a machine of the character described, the combination with a rotatable type plate bed, of a rotatable type bed, means for feeding type plates to said plate bed, a salutation member rotatable with said type bed and carrying a plurality of different salutations, and means set in motion by the passage of a type plate through the machine for causing said salutation device to present a salutation to printing position to agree with the address carried on the type plate.

51. In a machine of the character described, the combination with a rotary type bed, of a rotary type plate bed, means for 130

feeding type plates to said plate bed, a rotary salutation member arranged to rotate on its own axis and also to rotate with said type bed, and means for automatically rotating said salutation member on its own axis to cause the same to present a salutation to printing position to agree with the address on the type plate.

52. In a machine of the character described, the combination with a rotary type bed, of a rotary type plate bed, means for feeding type plates to said plate bed, a salutation carrying member rotatable with said type bed and also arranged to rotate on its own axis, and means for automatically rotating said salutation member to cause the same to present different salutations to a printing position.

53. In a machine of the character described, the combination with a rotary type bed, of a rotary freely movable type plate bed, a platen coöperating therewith to form an impression, means for feeding type plates to said type plate bed, a rotary salutation member rotatable with said type bed and carrying a plurality of different salutations, and means for automatically rotating said salutation member on its own axis to cause the same to present different salutations to printing position.

54. In a machine of the character described, the combination with a rotatable printing bed, of a salutation member having a plurality of salutation carrying faces rotatable therewith and arranged to rotate on its own axis, means for automatically rotating said salutation member on its own axis to present different salutation carrying faces to printing position, and means for locking said salutation member against further rotation on its own axis during the printing operation.

55. In a device of the character described, the combination with a rotary type plate bed, of a salutation carrying member having a plurality of faces arranged to rotate with said bed and arranged to rotate on its own axis, a pair of arms having a rack and pinion connection with said salutation mechanism, and means arranged to engage said arms and hold the same against movement to cause said rack and pinion connection to rotate said salutation member without interfering with its rotative movement with the type bed.

56. In a machine of the character described, the combination with a rotatable type bed, of a salutation member having a plurality of salutation carrying faces mounted to rotate therewith and arranged to rotate on its own axis, a pair of arms rotatable with said bed and having a rack and pinion connection with said salutation member, one of said connections being arranged to rotate said salutation member on

its own axis in one direction, and the other connection being adapted to rotate said salutation member on its own axis in the opposite direction, and automatically operated stops arranged to engage said arms to hold the same against rotation and cause said rack and pinion connection to rotate the salutation carrying member on its own axis.

57. In a machine of the character described, the combination with a rotatable type bed, of a rotatable type plate bed, type plates, means for feeding said type plates one at a time to said type plate bed, a salutation member mounted to rotate with said type bed and rotatable on its own axis, a pair of rotatable arms having a rack and pinion connection with said salutation member, a plurality of stops arranged to project into the path of said arms during the rotation of said salutation member with the type bed to hold said arms against movement and cause said salutation member to rotate on its own axis, a plurality of trigger members arranged to hold said stops out of engaging position, and trigger tripping members carried on said plates arranged to trip the triggers to permit the stops to move into engaging position.

58. In a machine of the character described, the combination with a rotatable type bed, of a rotatable type plate bed, a plurality of type plates arranged to be fed one at a time to the type plate bed, a salutation member having a plurality of faces, rotatable with said type bed, a pair of rotatable arms having a rack and pinion connection with said salutation member, a plurality of stops arranged to engage said arms to hold the same against movement and cause said rack and pinion connection to rotate said salutation member on its own axis during its rotation with the type plate bed, a plurality of triggers for holding said stops against moving into engaging position, a plurality of type plate operated tripping levers for tripping said triggers, and means for relieving the tension between the triggers and the stops during the period the type plates are operating said levers.

59. In a device of the character described, the combination with a rotatable type bed, of a rotatable type plate bed, a plurality of type plates arranged to be fed one at a time to said type plate bed, a salutation member rotatable with said type bed and having a plurality of faces, said salutation member being arranged to be rotated on its own axis during its rotative movement with said type bed, a pair of arms mounted to rotate with said type bed and having a rack and pinion connection with said salutation member, the rack and pinion connection of one of said arms being arranged to rotate the salutation member on its own axis in one direction and the

- rack and pinion connection of the other arm being arranged to rotate the salutation member in an opposite direction on its own axis, a plurality of stops arranged to engage said arms to hold them against rotating to cause the rotation of the salutation member on its own axis, a plurality of triggers arranged to prevent said stops from engaging said arms, a plurality of trigger tripping levers for tripping said triggers arranged in the path of the type plates as they pass through the machine, and members on said type plates arranged to engage said levers to trip the triggers.
60. In a machine of the character described in which type plates are used in making an impression, the combination with a rotary bed, of a rotary platen co-operating therewith for making an impression, and means arranged to be automatically set in motion by the passage of a type plate through the machine for throwing said platen out of pressure position.
61. In a device of the character described, the combination with rotary printing means, of means for feeding thereto a type plate, a paper feeding means for delivering a single sheet at a time to said printing means, means for preventing the delivery of a sheet of paper to said printing means, and means thrown into operative position by the passage of a type plate through the machine for maintaining said preventing means in operative position for a predetermined length of time.
62. In a machine of the character described, the combination with a printing mechanism, of a paper feeding mechanism for delivering impression receiving sheets to said printing mechanism, a type plate feeding mechanism for delivering type plates to said printing mechanism, and means operated by the passage of a type plate for rendering said printing mechanism inoperative and for preventing the passage of an impression receiving sheet through said printing mechanism for a predetermined interval of time.
63. In a machine of the character described, the combination with a printing mechanism comprising type beds and a pressure platen, of means for feeding type plates to said printing mechanism, and means for automatically throwing said platen out of pressure position upon the passage to the printing mechanism of a predetermined type plate.
64. In a machine of the character described, the combination of a printing mechanism including a pressure platen, means for normally holding said platen in impression-forming position, means actuated by the passage of a type plate toward the impression-forming position to release said holding means, and means for automatically

moving the platen to non-impression-forming position when released.

65. In a machine of the character described, the combination with a printing mechanism having as one element thereof a platen normally held in impression-forming position, of means for feeding type plates to said printing mechanism, means for automatically moving said platen bodily out of impression-forming position upon the passage of a predetermined type plate toward said platen and for returning said platen to impression-forming position after the type plate has passed said platen.

66. In a machine of the character described, the combination with a printing mechanism having as one element thereof a rotary platen, of means tending to move said platen out of printing position, cam members holding said platen against said movement, and automatic means for rotating said cam members to first permit said platen to rise to non-pressure position and then draw said platen to pressure position upon the passage of a predetermined type plate.

67. In a machine of the character described, the combination with a printing mechanism having as one element thereof a rotary platen, of means for feeding type plates to said printing mechanism, said platen having a tendency to move to non-pressure position, cam members for holding said platen against movement to non-pressure position, means for rotating said cam members, normally disconnected therefrom, and means for connecting said rotative means to the cam members operated by the passage of a predetermined type plate to the printing mechanism.

68. In a machine of the character described, the combination with a printing mechanism having as one element thereof a rotary platen, of means normally tending to move said platen to non-pressure position, cam members arranged to hold said platen against movement to non-printing position, means for rotating said cam members, a lever for holding said means out of operative position, a latch for holding said lever, a trigger for tripping said latch, and means carried on certain of the type plates for tripping said trigger.

69. In a machine of the character described, the combination with a printing mechanism having as one element thereof a rotary platen, of means for feeding type plates to said printing mechanism, means tending to normally move said platen into non-pressure position, cam members holding said platen against said movement, means for rotating said cam members, a lever normally holding said means disconnected from said cam members, a latch connected with said lever, a trigger for

tripping said latch, means carried on certain of the plates for tripping said trigger, and means for relieving the engaging tension between said latch and trigger as the 5 trigger is tripped by the type plate.

70. In a machine of the character described, the combination with a printing mechanism having as one element thereof a rotary platen, of means for feeding type 10 plates to said printing mechanism, means normally tending to move said platen to non-pressure position, cam members for holding said platen against such movement, means for rotating said cam members, a 15 clutch for connecting said means with said cam members and normally in disconnected position, a latch holding said means, a plurality of tripping members for tripping said latch, and means on the type plates for 20 operating said tripping members.

71. In a machine of the character described, the combination with a printing mechanism having as one element thereof a rotary platen, of means for feeding type 25 plates to said printing mechanism, means normally tending to move said platen out of pressure position, cam members for holding said platen against movement, means for rotating said cam members having as elements 30 thereof a plurality of depressors arranged to be moved into or out of engaging position, and means carried on type plates arranged to engage said depressors.

72. In a machine of the character described, the combination with a printing mechanism having as one element thereof a rotary platen, of means for feeding type 35 plates to said printing mechanism, means tending to move said platen out of pressure position, means for holding said platen in pressure position, means for operating said holding means to permit said platen to move to non-pressure position, a lever for holding said operative means normally out of connection with said holding means, a latch holding said lever, a trigger for tripping said latch, and a plurality of depressor members arranged to be engaged by members on the type plates for operating said 45 trigger, said depressor members being arranged to be moved into or out of position to be engaged by said means carried on said type plates.

73. In a machine of the character described, the combination with a printing mechanism having as one element thereof a platen roller, of means for feeding type 55 plates to said printing mechanism, means tending to move said platen to non-pressure position, means for holding said platen against such movement, means for operating said holding means to permit the platen to move, a lever for holding said operating means normally disconnected from the holding 60 means, a latch engaging said lever, a 65

trigger for tripping said latch, members on the type plates arranged to operate said trigger, and means for relieving the holding pressure between said trigger and latch at the period said trigger is operated.

74. In a device of the character described, the combination with a printing mechanism having as one element a rotary platen, of means for feeding type plates to said printing mechanism, means tending to move said platen into non-pressure position, cam members for holding said platen against movement by said means, a rack and pinion connection including a clutch between said cam members arranged to operate said cam members to first permit said platen to move to non-printing position and then to move said platen to pressure position when said clutch is engaged, and means normally holding the parts of said clutch out of engagement arranged to be operated by the passage of a type plate to said printing mechanism, to permit said clutch to engage for a predetermined period only.

75. In a machine of the character described, the combination with a printing mechanism, of a plurality of type plates, feeding mechanism for delivering type plates to said printing mechanism, and continuously actuated sheet feeding mechanism for feeding sheets one at a time to said printing mechanism, and means set in motion by the passage of a type plate to said printing mechanism for arresting said sheet feeding mechanism during the passage of the type plate through the printing mechanism.

76. In a machine of the character described, the combination with a printing mechanism, of a type plate feeding mechanism for delivering type plates to said printing mechanism, a paper feeding mechanism having stop members arranged to be intermittently projected into the path of the sheet of paper to time the delivery of the same to the printing mechanism, and means set in motion by the passage of a type plate to the printing mechanism for maintaining said stop members in the path of a sheet for a predetermined length of time.

77. In a machine of the character described, the combination with a printing mechanism, of means for feeding type plates thereto, paper feeding mechanism for delivering sheets of paper one at a time to said printing mechanism, and means adapted to be positioned in the path of the paper for rendering said paper feeding mechanism inoperative upon the passage of a predetermined type plate to said printing mechanism.

78. In a machine of the character described, the combination with a printing mechanism, of means for feeding type plates thereto, continuously actuated means for

feeding impression-receiving sheets one at a time to said printing mechanism, and means for intermittently arresting said paper feeding means, said arresting means being set in motion by the passage of a type plate to the printing mechanism.

79. In a machine of the character described, the combination with a printing mechanism, of means for feeding type plates thereto, continuously actuated means for feeding impression-receiving sheets one at a time thereto, means for automatically arresting said paper feeding means upon the passage of a predetermined type plate to the printing mechanism and again rendering said paper feeding means operative after the type plate has passed through the printing mechanism.

80. In a machine of the character described, the combination with a printing mechanism, of means for feeding type plates to said printing mechanism, means for feeding impression receiving sheets one at a time to said printing mechanism, having as one element thereof stop members in the path of the sheets, means for intermittently moving said members out of the path of the sheets, and automatic means for rendering said moving means inoperative.

81. In a machine of the character described, the combination with a printing mechanism, of means for feeding type plates thereto, means for feeding impression receiving sheets one at a time to said printing mechanism, having as one element thereof stop members, means for intermittently retracting said stop members from the path of the paper, means for rendering said retractive means inoperative normally disconnected from said retractive means, and means operated by the passage of a predetermined type plate to the printing mechanism for connecting the said means to the retractive means.

82. In a machine of the character described, the combination with a printing mechanism, of means for feeding type plates thereto, means for feeding impression receiving sheets one at a time to said printing mechanism and having as one element thereof stop members, means for intermittently retracting said stop members from the path of the sheets of paper, a lever for disconnecting said retractive means from the stop members, a latch for holding said lever in inoperative position, a trigger for tripping said latch, and means carried by predetermined type plates for tripping said trigger.

83. In a machine of the character described, the combination with a printing mechanism, of means for feeding type plates thereto, means for feeding impression receiving sheets one at a time to said printing mechanism and having as one element thereof stop members, means for intermittently

retracting said stop members from the path of the sheets, mechanism for rendering said retractive means inoperative, a lever normally holding said mechanism disconnected therefrom, a latch connected with said lever, a trigger for tripping said latch, means carried on predetermined type plates for tripping said trigger, and means for relieving the engaging tension between said latch and trigger as the trigger is tripped by the type plate.

84. In a machine of the character described, the combination with a printing mechanism, of means for feeding type plates thereto, means for feeding impression receiving sheets thereto having as one element stop members, means for intermittently retracting said stop members from the path of the paper, mechanism for rendering said retractive means inoperative, comprising a lever, a latch holding said lever, a plurality of tripping members for tripping said latch, and means on the type plates for operating said tripping members.

85. In a machine of the character described, the combination with a printing mechanism, of means for feeding type plates thereto, means for feeding impression receiving sheets to said printing mechanism having as one element thereof stop members, means for automatically retracting said stop members from out of the path of the sheets, mechanism for rendering said retractive means inoperative having as one element thereof a plurality of depressors arranged to be moved into or out of engaging position, and means carried on predetermined type plates arranged to engage said depressors.

86. In a machine of the character described, the combination with a printing mechanism, of means for feeding type plates thereto, means for feeding impression receiving sheets one at a time to said printing mechanism, having as one element thereof stop members, means for intermittently retracting said stop members from the path of the sheets, means for rendering said retractive means inoperative, comprising a lever, a latch holding said lever, a trigger for tripping said latch, and a plurality of depressors arranged to be engaged by members on the type plates for operating said trigger, said depressor members being arranged to be moved into or out of position to be engaged by the members on the type plates.

87. In a machine of the character described, the combination with a printing mechanism having as one element thereof a platen, of means for feeding type plates to said printing mechanism, means for feeding impression receiving sheets one at a time to said printing mechanism having as one element thereof stop members, means for inter-

mittently retracting said stop members from the path of the sheet, and means for automatically throwing the platen out of pressure position and rendering said retractive means inoperative upon the passage of a predetermined type plate to the printing mechanism, and returning said platen to pressure position and rendering said retractive means operative after the type plate has passed through the printing mechanism.

88. In a machine of the character described, the combination with a printing mechanism, of type plate feeding mechanism for delivering type plates thereto, impression receiving sheet feeding mechanism for delivering sheets one at a time to said printing mechanism, means for rendering said printing mechanism inoperative, means for rendering said feeding mechanism inoperative, a lever for holding said means out of operative position, a latch for holding said lever, a trigger for tripping said latch, and means carried on predetermined type plates for tripping the trigger.

89. In a machine of the character described, the combination with a printing mechanism, of type plate feeding mechanism for delivering type plates to said printing mechanism, impression receiving sheet feeding mechanism for delivering sheets one at a time to said printing mechanism, means for rendering said sheet feeding mechanism inoperative, means for rendering said printing mechanism inoperative, a lever for holding both said means out of operative position, a latch for holding said lever, a trigger for tripping said latch, means carried on predetermined type plates for tripping said trigger, and means for relieving the engaging tension between said latch and trigger as the trigger is tripped by the type plates.

90. In a machine of the character described, the combination with a printing mechanism, of type plate feeding mechanism for delivering type plates thereto, impression receiving sheet feeding mechanism for delivering sheets one at a time to said printing mechanism, means for rendering said paper feeding mechanism inoperative, means for rendering said printing mechanism inoperative, a lever for holding both said means out of operative position, a latch for holding said lever, a trigger for releasing said latch, a plurality of depressors for operating said trigger, and means on the type plates for operating said depressors.

91. In a machine of the character described, the combination with a printing mechanism, of type plate feeding mechanism for delivering type plates thereto, impression receiving sheet feeding mechanism for delivering sheets to said printing mechanism, means for rendering said printing mechanism inoperative, means for rendering

said sheet feeding mechanism inoperative, 65 a lever for holding both said means out of operative position, a latch holding said lever, a trigger for releasing said latch, and a plurality of depressor members for operating said trigger arranged to be moved into 70 or out of position to be engaged by tripping means carried by the type plates.

92. In a machine of the character described, the combination with a printing mechanism, of means for feeding type plates 75 thereto, means for feeding impression receiving sheets one at a time to said printing mechanism, and a sheet delivering mechanism having a relatively stationary member and a movable member, said movable member being arranged to be moved into a position to receive the edge of the sheet as it is delivered to the printing mechanism and to be moved out of the path of the type plate as it passes through the printing 85 mechanism.

93. In a machine of the character described, the combination with a printing mechanism, of means for feeding type plates thereto, means for feeding impression receiving sheets thereto, and a sheet delivering mechanism having a relatively stationary member provided with sheet conveyers and a reciprocating member arranged to be projected into the path of the edge of the sheet 95 as it is delivered to the printing mechanism and move upwardly and rearwardly as the sheet progresses through the printing mechanism.

94. In a machine of the character described, the combination with a printing mechanism, of means for delivering type plates to said printing mechanism, means for delivering impression receiving sheets to said printing mechanism, a sheet delivering 100 mechanism comprising a relatively stationary member having a sheet conveyer and a relatively movable member, and a rack and gear mechanism for moving said movable member into the path of the edge of the 110 sheet as it is delivered to said printing mechanism and then moving said movable part with the sheet as it passes through the printing mechanism.

95. In a machine of the character described, the combination with a printing mechanism, of means for delivering type plates thereto, means for delivering impression receiving sheets to said printing mechanism, a sheet delivery mechanism having a 115 relatively stationary member provided with sheet conveying mechanism and a relatively movable member, a rack and gear mechanism and cams, for moving said movable member into the path of the edge of the 120 sheet as it is delivered to the printing mechanism and then retracting the same as the sheet is fed to the printing mechanism,

and raising the front edge thereof as the sheet passes through the printing mechanism.

96. In a machine of the character described, the combination with a movable type bed, of an independently and freely rotatable type plate support, a platen, and means for delivering type plates to said support in position to be engaged by said platen, said platen being arranged to move the plates beneath the same on said support at the same surface speed as that at which the type bed is driven.

97. In a machine of the character described, the combination with a rotating type bed, of a rotating platen, a rotating plate support and means for delivering type plates to a point where they may be engaged by said platen, said platen being arranged to move the type plates beneath the same at the same speed as the surface speed of the type bed.

98. In combination in addressing machinery, impression means, selective address plates and selector means for selecting the plates to be printed, said selector means comprising a plurality of feelers, each adjustable into and out of operative position in relation to the address plates.

99. In combination in addressing machinery, impression means, selective address plates, and selector means for the ad-

dress plates having a plurality of feelers, each adjustable to contact with the plates or to miss the same, operating connections 35 for the selector means, and connections controlled from the selector means for operating the impression member.

100. In combination in addressing machinery, impression means, selective address 40 plates having contact portions which are adjustable, a selector for the plates to be printed comprising feelers to engage said contact portions, the said feelers being adjustable to hit or miss the said contact portions, and means controlled by said selector for determining the performance of a function of the machine.

101. In an addressing machine, the combination of impression means, selective address plates provided with contact portions, a selector having pivoted feeler fingers held in position in alignment with the plate or out of alignment therewith, and connections controlled by the selector for determining the making of impressions.

In witness whereof, I have hereunto subscribed my name in the presence of two witnesses.

DAVYDD C. HUGHES.

Witnesses:

W. PERRY HAHN,
E. R. KING.
